UNITED STATES PATENT OFFICE.

EPHRIAM G. HARRISON, OF PROVO CITY, UTAH.

WINDOW-SHADE HOLDER.

1,229,074.

Specification of Letters Patent.

Patented June 5, 1917.

Application filed February 16, 1916. Serial No. 78,762.

To all whom it may concern:

Be it known that I, EPHRIAM G. HARRISON, a citizen of the United States, residing at Provo City, in the county of Utah and State of Utah, have invented new and useful Improvements in Window-Shade Holders, of which the following is a specification.

This invention relates to window shade 10 holders and it consists in the novel features hereinafter described and claimed.

An object of the invention is to provide a holder of simple structure adapted to be applied to the stick of a window shade, and 15 having a spring pressed member engageable with the window frame, whereby the shade may be held against swinging movement in the frame, and also may be held at a desired point along the frame against the tension 20 of the spring which usually actuates the shade roller.

With the above object in view the holder comprises a hollow body provided at one 25 side with converging flanges adapted to receive between them the stick of the window shade. Securing devices are adapted to be passed transversely through the said flanges and the window shade stick, whereby the body is held securely in position upon the 30 said shade and stick. Inasmuch as the sticks used in window shades have converging sides, the said flanges will fit snugly at the opposite sides of the stick and the space between the outer edges of the flanges is 35 less than the major transverse thickness of the stick, so that the stick cannot pull out from between the flanges in the event that the securing devices become detached from the flanges and stick. Also this arrangement 40 relieves the securing devices from strain and therefore, they will not have a tendency to split the stick when the device is in use.

The said body is provided at its side and 45 in the vicinity of one end with a longitudinally disposed slot, and the body is further provided at the same side and in the vicinity of its opposite end with an outwardly standing lug. A bar is slidably mounted in the 50 body and carries at its outer end a head adapted to engage the side of the window frame. A handle is mounted upon the bar and is disposed through the said slot. A spring is located in the body and bears at 55 one end against the end of the body and at its other end against the said handle, and

is under tension with a tendency to hold the head of the bar away from the adjacent edge of the body.

In the accompanying drawing:

Figure 1 is a side elevation of the window shade holder.

Fig. 2 is an end elevation of the same, showing it applied to a shade, the shade and stick thereof being shown in section.

Fig. 3 is a longitudinal sectional view of the shade holder.

Fig. 4 is a transverse sectional view of the same.

The window shade holder comprises a 70 body 1 which is rounded at its lower side and provided at its top with a flat surface 2. The body 1 is provided at its opposite sides and at the edges of the flat surface 2 with converging flanges 3, adapted to lie at the 75 opposite side of the loop in a window shade which receives the stick, as best shown in Fig. 2 of the drawing. Securing devices 4, as for instance screws, pass transversely through the flanges 3, and enter the stick of 80 the window shade and serve in part as means for securing the holder in position upon the shade.

The body 1 is provided at one side and in the vicinity of one end thereof with longitudinally disposed slot 5, and the said body is provided at the same side and in the vicinity of its other end with an out-standing lug 6. A bar 7 is slidably mounted in the body 1 and the said bar is provided at its outer end with an enlarged head 8. A handle lug 9 is attached to the bar 7 at a point between the ends thereof, and the said handle lug is disposed through the slot 5 of the body 1. A spring 10 is located in the body 1 and bears 95 at one end against the end of the body and at its other end against one side of the handle lug 9, and the said spring is under tension with a tendency to hold the head 8 of the bar 7 normally away from the adjacent edge of the body 1.

In practice one or two of the said bodies 1 may be applied to the lower edge of a window shade with their flanges 3 at the opposite sides of the stick of the shade. The 105 said bodies, when two are used, are positioned in the vicinity of the side edges of the shade, consequently the bars 7 may project beyond the side edges of the shade and the heads 8 thereof may engage the sides of the 110 window frame. Thus the frictional contact is provided between the holders and the win-

dow frame to prevent the shade from swinging in the breeze, and also to hold the shade against the winding tension of the shade roller upon which it may be mounted.

In view of the fact that the flanges 3 of each body 1 converge at their upper ends toward each other, the said flanges may fit snugly against the sides of the loop which receives the window stick, in view of the fact that the sides of the window stick converge, as best shown in Fig. 2. The space between the upper edges of the flanges 3 is less than the major transverse dimension of the window stick; consequently the stick and the shade are securely held between the flanges and the securing devices 4 are relieved of strain, when pull is exerted upon the holder. Therefore, the said securing devices, when the holder is operated, will not have a tendency to split the stick. Furthermore, the disposition of the flanges 3 is such as to maintain the holder in proper position upon the window shade in the event that the securing devices 4 should become detached.

When it is desired to shift the shade vertically, the thumb is placed against the outer side of the lug 6 and the forefinger over the outer side of the handle lug 9 and the lug 9 is forced toward the lug 6 against the tension of the spring 10. Thus the head 8 of the bar 7 is withdrawn from its engagement with the side of the window frame, and the window shade is rendered free to

move vertically. When the shade is adjusted to a desired position the lug 9 is released and under the influence of the spring 10 the bar 7 is moved in an outward direction, whereby the head 8 engages the side of the window frame, and holds the shade at the adjusted position.

Having described the invention what is claimed is:—

A window shade holder comprising a hollow body provided at its top with converging flanges which extend the full length of the body, said body having at its side and in the vicinity of the end thereof a longitudinally disposed slot, said body having at the same side an out-standing lug, a bar movably mounted in the body and provided at its outer end with an enlarged head, a handle lug mounted upon the bar and disposed through the slot and a spring located in the body and bearing at one end against the end of the same and at its other end against the side of the handle lug and being under tension with a tendency to normally hold the head of the bar away from the adjacent end of the body.

In testimony whereof I affix my signature in presence of two witnesses.

EPHRIAM G. HARRISON.
